CLAIM

The ornamental design for a package containing a debridement sponge, as shown and described.

DESCRIPTION

FIG. 1 is a perspective view of a package containing a debridement sponge;

FIG. 2 is a front elevation view of FIG. 1;

FIG. 3 is a back elevation view of FIG. 1;

FIG. 4 is a right side elevation view of FIG. 1, where a left side elevation view is not provided as it is a mirror image of the right side elevation view;

FIG. 5 is a bottom plan view of FIG. 1; and,

FIG. 6 is a top plan view of FIG. 1.

The broken lines in FIGS. 1-6 form no part of the claimed design.

1 Claim, 6 Drawing Sheets
